UNITED STATES PATENT OFFICE.

JOSEPH A. WESTER, OF WEST FRANKFORT, ILLINOIS.

MINER'S ACETYLENE-LAMP.

1,114,208.

Specification of Letters Patent. Patented Oct. 20, 1914.

Application filed March 24, 1913. Serial No. 756,538.

To all whom it may concern:

Be it known that I, JOSEPH A. WESTER, citizen of the United States, residing at West Frankfort, in the county of Franklin and State of Illinois, have invented certain new and useful Improvements in Miners' Acetylene-Lamps, of which the following is a specification.

My invention relates to new and useful improvements in combined gas generators and lamps, and the object of my invention is to provide a miner's acetylene lamp which may be worn upon the cap of the miner in the same manner in which the coal oil lamps now commonly employed are worn.

A still further object of the invention is to provide a lamp having two burners and two separate and independent generating chambers and means for supplying gas from each chamber to its burner.

With these and other objects in view, my invention will be more fully described, illustrated in the accompanying drawings and then specifically pointed out in the claims which are attached to and form a part of this application.

In the drawings: Figure 1 is a central vertical sectional view of my improved miner's lamp showing the construction of the lamp and also the manner in which it is attached to a miner's cap. Fig. 2 is a section on the line 2—2 of Fig. 1. Fig. 3 is a section on the line 3—3 of Fig. 1. Fig. 4 is a fragmentary sectional view of one of the valves employed in my lamp. Fig. 5 is a fragmentary perspective view of a conventional form of miner's cap showing the positioning of certain lamp engaging and supporting plates.

Corresponding and like parts are referred to in the following description and indicated in all the views of the accompanying drawings by the same reference characters.

The combined lamp and generator proper includes a lower body portion 10 forming the carbid and gas generating chamber of the main generator and an upper body member 11 forming the water reservoir for the main generator and also including both the carbid chamber and water reservoir of the supplemental generator. The body member 10 is formed of metal and is preferably cylindrical in shape, being closed at its lower end by a bottom 12 and having a reduced upper end terminating in a threaded flange 13 adapted for engagement

within the downwardly directed threaded flange 14 of the upper body member 11, the flange 14 of the upper body member being flared at its free edge, as shown at 15, to clamp a packing ring 16 between it and the inclined upper wall portion of the lower body member 10 and so form a gas-tight joint.

The upper body portion 10, as clearly shown in Fig. 2 of the drawings, is substantially elliptical in horizontal section and reduced at its lower end to merge into the cylindrical flange or ring 14 to permit engagement with the lower body section. The body section 11 is closed at its lower end by a bottom 17 so positioned as to preferably be spaced from the upper edge of the flange 13 of the lower body section when the sections are united, and the upper body section is closed at its upper end by a top 18. An inner casing 19 coacts with the walls of the upper body section 11 to form a substantially cylindrical inner compartment 20 located in the forward portion of the upper body member and the function of which will be hereinafter explained. The remainder of the upper body section forms the water reservoir of the main generator while the entire lower body section forms the carbid and gas generating chamber of the main generator. A vertical cylindrical sleeve 21 extends by its upper end through the bottom 17 of the upper section 11, being secured thereto and having its upper end internally beveled to provide a valve seat 22. A valve 23 normally engages in this valve seat and is provided with a cylindrical portion extending through the sleeve and having a squared part immediately below the sleeve which passes through a squared opening formed in the closed lower end of an outer perforated sleeve 21'. The terminal of this cylindrical portion is threaded to receive a nut 24' by means of which the outer sleeve is clamped in place.

The portion 24 is provided throughout its entire length with a helical groove, thread or channel 26, the upper end of said portion immediately adjacent the valve 23 being provided with an encircling groove 26' from which a groove 26'' leads at right angles to the main groove 26. This valve 23 is provided with a valve stem 27, the upper end of which is threaded through a thickened portion 28 of the top 18, being provided at its end with a milled head 29.

by means of which an outer sleeve may be rotated to raise or lower the valve 23 from its seat 22. It will be apparent that when the valve is raised from its seat the water contained in the main chamber of the upper body section will be uniformly fed to the carbid chamber or lower section and that this feeding of water will be uniform irrespective of any sudden shocks or jars received by the lamp as all water passing from one section to the other must flow through the helical groove 26. It will further be apparent that the rotary and upward movement of the outer perforated sleeve will break up and loosen any carbid crustations and permit the water to reach fresh carbid, this outer sleeve being spaced from the inner sleeve a sufficient distance to allow the water to pass upwardly between the two sleeves and through the perforations of the outer sleeve. The top 18 of the upper section is provided with a filling opening 30 which is normally closed by a screw cap 31.

25 The wall 19 and that portion of the wall of the upper section coacting with the wall 19 to form the chamber 20 are internally threaded at their upper portions to engage the threaded wall 32 of a substantially cylindrical water reservoir indicated as a whole by the numeral 33 and including the main body 32, the funnel-shaped bottom 34 and top 35, the latter being provided with a laterally directed encircling flange 36 which

30 seats upon the top of the upper body section when the reservoir is in place, and with upwardly directed spaced ears 36' adapted for engagement by a screw driver or other implement and providing means for rotating the reservoir. The bottom 34 of this supplemental water reservoir is provided with a valve seat 37, a valve sleeve 38 corresponding to the valve sleeve 21 and a valve 39 identical in construction with the

35 valve 23 and having an extended portion threaded to correspond to the extended portion of the former valve, this extended portion projecting through the sleeve and being secured in the closed end of an outer sleeve 38' corresponding to the outer sleeve 21'. The valve stem 41 of this valve is threaded through the top of the supplemental reservoir and terminates in a milled head 42. The top of the reservoir is provided with a filling opening 43 normally closed by a screw cap 44.

Extending laterally from the forward portion of the upper body section is a casing 45 substantially elliptical in shape and 60 divided centrally at its forward end by a partition wall 46 forming tubular extensions the upper of which communicates through the rear portion of the casing 45 with the supplemental generating chamber. A vertical partition wall cuts off communication

between the lower tubular extension and said chamber. The inner end of the casing 45 is packed with mineral wool or other suitable filtering material held in place between spaced screens, the inner of which, 47', is 70 mounted between slides 47''. A pipe 48 leads from the lower tubular extension near the outside of the lamp and has its free end passed inwardly through the wall of the upper lamp section immediately below the bottom thereof. An apertured plate 48' is seated in spaced relation below the bottom of the upper section to act as a retaining member for a packing of mineral wool, and this plate is held in its spaced relation by inwardly directed lugs 48''.

A burner is positioned in the outer end of each of the tubular extensions of the casing 45, and the upper burner is normally closed and protected by a cap 45' which is held in 85 either operative or inoperative position by a spring 46'' engaging about its shank and mounted in a housing. The front portion of the wall of the upper body section is provided adjacent the top thereof with a U-shaped bracket 49 adapted to detachably engage the downwardly directed terminal of an arm 50 carried by a reflector 51, the lower edge portion of which is bifurcated as at 52 to straddle the burner, tubes, and the upper portion of which is curved upwardly and forwardly to cast the light from the burners downwardly in advance of a miner wearing the lamp upon his cap. The lower portion of the lower body member is fluted or otherwise provided with ribs 50' in order that it may be readily grasped and turned to disconnect it from the upper body member.

As a means for attaching the above lamp to a miner's cap, I have provided the upper body portion at a point opposite the burners with a rearwardly and downwardly directed hook 53, while plates or bracket arms 54 are secured to the flange portion 14 of the upper body section having their intermediate portions secured to each as shown at 55 to extend radially from the flange 14 and having their end portions oppositely directed at right angles to the immediate portion, as shown at 56. The miner's cap, which is conventionally shown at 57, carries upon its top and front a plate 58 of metal or other suitable material provided with intersecting grooves or channels 59 in its upper face and having an opening 60 formed at the intersection of these grooves and registering with an opening 61 formed in the top of the cap. The plate is provided in front with a plate 62 having upwardly directly spaced spring arms or clips 63 adapted to receive the oppositely directed terminals 56 of the lamp brackets when the downwardly directed terminal of the hook 53 is passed through the openings 60 and 61. The manner of attaching the lamp to the cap will be 130

readily understood from this description, particularly in view of the showing in Figs. 1, 3 and 5 of the drawings. The grooves formed in the plate 58 are merely to assist in leading the downwardly directed terminal of the hook into the perforation of the plate in order to permit the right positioning of the lamp when the cap is on the miner's head.

The operation of the lamp will be readily understood and but slight description of the same is necessary. It must be borne in mind that because of explosive gases commonly met with in mines, any free flame unprotected by a gauze housing is a great source of danger and for this reason if any candle or lamp worn by a miner goes out it is practically impossible for him to light it without leaving the mine. Furthermore, it is frequently dangerous for any miner to move about in a mine without a light. It is for this reason that I have provided the lamp with two entirely separate and independent gas generating chambers and water reservoirs and with two burners, so arranged that either one may be lighted from the other. The chambers are filled with carbid and both water reservoirs with water. The valve 39 controlling the supply of water to the supplemental generating chambers is closed, however, while the valve 23 is opened to permit the feeding of water to the main carbid chamber. Gas therefore is generated only in the main carbid chamber and the lower burner is the only burner normally used. If at any time the light given by the lamp grows dim, either through exhaustion of the carbid or the complete use of the water in the main generator, the miner, being warned by the feebleness of the light, immediately opens the valve of the supplemental generator, removes the cap 45' and as soon as gas is generated in said generator it passes to the upper burner which is immediately ignited from the lower burner. This supplemental generator contains sufficient water and carbid to maintain the necessary light while the miner reaches a point where he can safely recharge and relight the lamp.

It will of course be understood that when the lamp is used in mines containing explosive gases the lamps will be protected by some suitable screen of foraminous material but as such a screen does not form any part of the present invention it has been omitted from the drawings to permit the more clear showing of the actual structure of the burner tubes.

I do not wish in any way to limit myself to the specific details of construction illustrated in the drawings and described in the above specification, as various minor changes within the scope of the appended claims may at any time be made without in the slightest degree departing from the spirit of my invention.

What I claim is:

1. A miner's acetylene lamp including a body having upper and lower sections, the lower section forming a main generating chamber and the upper section forming a main water reservoir for the said generating chamber and a supplemental generating chamber, a water reservoir detachably carried by the upper section and adapted to furnish water to the supplemental generating chamber, a burner carried by the upper section and in communication with the main generating chamber, and an adjacent burner in communication with the supplemental generating chamber.

2. A miner's acetylene lamp including a lower body member open at its upper end, an upper body member closed at both ends and adapted for attachment to the lower body member, a partition wall dividing the upper body member into compartments, a manually operable valve arranged to provide communication between one of said compartments and the lower body member, a reservoir adapted for detachable engagement with the upper body member and forming a closure for the other compartment, a manually operable valve providing communication between said reservoir and its compartment, and burners carried by the upper body member and in communication with said latter compartment and the lower body member respectively.

3. A miner's acetylene lamp including a lower body member, an upper body member detachably secured to the lower body member and having a bottom forming a closure for the lower body member, a partition wall in the upper body member dividing the same into a water reservoir and a generating chamber, a valve controlling the flow of water from the reservoir to the lower body member, a water reservoir forming a closure for the generating chamber in the upper body member, a valve controlling the flow of water from said latter reservoir to the generating chamber of the upper body member, burners carried by the upper body member, communicating means between one of said burners and the generating chamber of the upper body member, and communicating means between the other of said burners and the generating chamber of the lower body member.

4. An acetylene lamp including a casing providing carbid chambers and water chambers, means for supplying water from the water chambers to the carbid chambers, a tubular casing open at its ends leading from one of the carbid chambers, a portion of the outer end of said casing being divided off by a partition, tubular connection between said divided off portion and the other carbid chamber, and burners fitted in the open outer ends of the tubular casing and its divided chamber.

5. An acetylene lamp including a casing provided with a plurality of water chambers and a plurality of carbid chambers, a plurality of burners arranged one immediately below the other, means for supplying gas from each generating chamber to one of the burners, and means for normally covering the discharge end of one of the burners.
- 10 6. An acetylene lamp including a casing provided with a plurality of water chambers and a plurality of carbid chambers, a plurality of burners arranged one immediately below the other, means for supplying
- gas from each generating chamber to one of the burners, and means for normally covering the discharge end of one of the burners, ¹⁵ said means including a cap mounted for reciprocatory and rotary movement, and a spring adapted to hold the cap in adjusted position.

In testimony whereof I affix my signature in presence of two witnesses.

JOSEPH A. WESTER. [L. S.]
